SAFETY DEVICE FOR HOISTING
MECHANISM

Edwin G. Halby, Marion, Ohio, assignor to The
Marion Steam Shovel Company, Marion, Ohio, a
corporation of Ohio

Application September 17, 1942, Serial No. 458,745

3 Claims. (Cl. 254—187)

This invention relates to a safety device for hoisting mechanism of the drum and cable type and is designed primarily to prevent the falling of the load in the event the hoisting drum is accidentally or inadvertently released from its driving mechanism. In hoisting mechanisms of this type the hoisting drum is usually connected with the driving mechanism by a clutch and it is common practice to lower the load by releasing the clutch and controlling the rotation of the drum in load lowering direction by means of a brake. If the drum is released by the failure of the clutch or the brake, or otherwise, it is free to rotate under the weight of the load on the cable and the load will fall with more or less disastrous results. In hoisting mechanisms of the boom type, such as cranes, excavating machines and the like, in which the boom is supported and moved to adjusted positions by a hoisting drum and cable the accidental or inadvertent release of the boom hoist drum is particularly serious as the falling of the boom will usually seriously damage or destroy the same, thus rendering the hoisting mechanism as a whole useless until the boom has been repaired or replaced.

One object of the invention is to provide a hoisting mechanism with a simple and efficient device which will operate automatically to prevent the falling of the load in the event the hoisting drum is accidentally or inadvertently released.

A further object of the invention is to provide such a device which will in no way interfere with the normal hoisting and lowering operations of the hoisting mechanism.

A further object of the invention is to provide such a device which will prevent any appreciable downward movement of the load when the driving mechanism is not operating and will retard the downward movement of the load to a safe speed when the driving mechanism is operating.

A further object of the invention is to provide such a device which will permit the drum to rotate in load lowering direction at a speed determined by the driving mechanism.

A further object of the invention is to provide such a device which will permit the drum to rotate in load lowering direction while the driving mechanism rotates in load lifting direction, and will limit such rotation of the drum to a speed determined by the driving mechanism.

Other objects of the invention may appear as the mechanism is described in detail.

In the accompanying drawings Fig. 1 is a plan view of the platform and hoisting mechanism of a crane equipped with my invention, with the gantry in section; Fig. 2 is a section taken on the line 2—2 of Fig. 1, looking in the direction of the arrows, with the gantry partly broken away; Fig. 3 is a longitudinal sectional view of a clutch mechanism forming a part of the safety device, taken on the line 3—3 of Fig. 1, looking in the direction of the arrows; Fig. 4 is a section taken on the line 4—4 of Fig. 3, showing the clutch mechanism in end elevation and partly broken away; Fig. 5 is a detail view of one of the supporting members of the clutch mechanism; Fig. 6 is a detail of an anchor for the spring for the clutch members; and Fig. 7 is a sectional detail view of a portion of the hoisting drum and the driving clutch and brake mechanism therefor.

In these drawings I have illustrated one embodiment of my invention and have shown the same as applied to a crane of a known type but it will be understood that the invention may take various forms and may be used in connection with hoisting mechanisms of various kinds.

The crane as here illustrated comprises a platform 10, which is usually mounted on a truck supported base, not here shown, for rotation about a vertical axis. A boom 11 is pivotally supported on the front end of the platform for vertical movement and, as here shown, is mounted on a supporting member or bracket 12. This boom is moved to and supported in adjusted positions by a cable 13 secured to the point of the boom, extending rearwardly therefrom about a sheave 14 carried by a gantry 15 and thence downwardly to a hoisting drum 16 to which it is secured and about which it is wound. In this particular arrangement a single length of cable is dead-ended on the boom but in many installations the end of the cable is anchored on the gantry and that portion of the cable between the boom and the gantry is passed about sheaves on the boom and gantry. The hoisting drum 16 is mounted on a shaft 17 for rotation thereon and is connected with and disconnected from the driving mechanism by means of suitable clutch mechanism. This driving clutch mechanism may be of any suitable character and, as here shown, it comprises a circumferential flange or clutch member 18 rigidly connected with the drum and having inner and outer friction surfaces. An internal friction band 19 is carried, in the present instance, by a gear 20 keyed to the shaft 17 and cooperates with the inner friction surface of the

clutch member 18 to connect the latter with and disconnect the same from the gear, the friction band being actuated by well known mechanism, not here shown. A brake band 19a cooperating with the outer friction surface of the clutch member 18 is also operated in a well known manner. A second hoisting drum 21 is also mounted on a shaft 17 to receive and operate the load elevating cable 22 which extends about a sheave 23 on the point of the boom. In the rear of the drum 21 there is shown at 24 a part of the mechanism for swinging the platform about its vertical axis. Neither the drum 21 nor the swinging mechanism forms any part of the present invention but it will be understood that the safety device may, if desired, be applied to the hoisting drum 21 in the same manner that it is applied to the boom hoisting drum 16, as hereinafter described. The driving mechanism for the hoisting drum 16 may be of any suitable type and, in the illustrated arrangement, it comprises a driving shaft 25 which is driven by a motor 26, the driving connection being here shown as a sprocket chain 27 extending about sprocket wheels secured respectively to the motor shaft and to the driving shaft 25. A pinion 28 rigidly secured to the driving shaft 25 meshes with the gear 20 of the clutch mechanism so that the gear 20 rotates in a direction opposite to the direction of rotation of the driving shaft 25 and when the clutch is set the hoisting drum will, of course, rotate in the same direction as the gear. In the hoisting operation of the mechanism here illustrated the driving shaft rotates in the direction of the arrow *b* on Fig. 2 and the hoisting drum rotates in the direction of the arrow *a*. When the boom has been adjusted to the desired position the brake band 19a is set to retain the boom in that position. When the boom is to be lowered the brake is released sufficiently to permit the slow rotation of the drum in load lowering direction. Should the connection between the hoisting drum 16 and the driving mechanism be accidentally or inadvertently interrupted, as by the failure of the driving clutch or brake, the drum 16 would be free to rotate out of control and the boom would fall.

To prevent the uncontrolled downward movement of the boom, or other load on the drum, in the event the drum is accidentally or inadvertently released I have provided a device controlled by the drum for automatically controlling its rotation so as to prevent or retard the rotation of the drum in load lowering direction. Preferably this device comprises a rotatable element drivingly connected with the drum for rotation therewith in either direction in which the drum may rotate and means controlled by the direction of rotation of that element for positively locking the same against rotation in a load lowering direction with relation to a second element. The device may conveniently be in the form of a one-way clutch, the two members of which are connected respectively with the driving mechanism and the drum for rotation thereby in opposite directions when the drum is rotated in load hoisting direction and for rotation in the same direction when the drum is rotated in load lowering direction, means being provided for automatically preventing the drum driven member from rotating in load lowering direction at a speed greater than the speed at which the other member rotates.

In the particular embodiment here illustrated

the one-way clutch comprises a member 29 rigidly secured to the shaft 17 and a second member 30 rotatably mounted on that shaft and having secured thereto a sprocket wheel 31 which is connected by a sprocket chain 32 with a sprocket wheel 33 rigidly secured to the drum. The member 30 is provided with a circumferential friction surface extending about the member 29 and here shown as the inner surface 34 of a flange 35 carried by and forming a part of the member 30, the flange being provided on its outer surface with heat radiating fins 36. The member 29 being rigid with the shaft 17 will of course rotate in a direction opposite to the direction of load hoisting rotation of the drum while the member 30, through the sprocket chain drive, will rotate in the same direction as the drum. Clutching devices, such as friction shoes 37, are arranged to engage the friction surface of the member 30 and are so connected with the member 29 that they will rotate with that member but may have a limited movement with relation thereto to enable them to be moved into and out of clutching engagement with the friction surface 34. The clutching devices 37 may be connected with or supported by the clutch member 29 in any suitable manner but preferably they are carried by supporting members mounted on the member 29 for rotation therewith and for movement with relation thereto about axes arranged on opposite sides of and spaced from the axis of rotation of the member 29. In the present construction the member 29 is provided with eccentric bearing surfaces 38 described respectively about axes arranged on opposite sides of the axis of the shaft 17, as indicated at 39 and 40 in Fig. 4, and are separated by a circumferential projection 50. The supporting members, 41, are shown as annular in form and the openings 42 thereof receive the respective eccentric bearing surfaces and are retained thereon by plates 43 rigidly connected with the clutch member 29. The two supporting members are provided respectively, on opposite sides of the clutch member 29, with arms 44 to which the friction shoes 37 are pivotally connected by pins 45. Each supporting member has in that side thereof opposite the pin 45 a slot 46 to receive the head of the shoe supporting pin 45 of the other supporting member. The pin and slot connections between the two members limit their relative movement on their respective eccentric bearing surfaces and maintain the same in proper relative positions, but the slots 46 are of a width sufficiently greater than the diameter of the pin heads to permit of a slight movement of each member with relation to the other member. The arrangement of the supporting members and friction devices is such that the latter are so supported with relation to the friction surface 34 that when the two clutch members, 29 and 30, rotate in opposite directions the movement of the supporting members on their eccentric bearing surfaces will permit the friction devices to be moved by the drum driven clutch member 30 to non-clutching positions, and when the clutch member 30 rotates in the same direction as the clutch member 29 and tends to rotate at a greater speed than the member 29 the shoes will be moved into clutching engagement with the friction surface 34 to connect the two members one with the other and the speed of rotation of the member 30 will be limited to that of the member 29. If the clutch member 30 tends to rotate in the last mentioned direction while the clutch member 29 is held against rota-

tion the clutching shoes will engage the friction surface 34 and positively lock the member 30 against such rotation.

In order that the clutching operation of the clutch shoes may be quickly effected when rotative force exerted on the clutch member 30 tends to rotate that member in the same direction as and with relation to the clutch member 29, the shoes are maintained at all times in light contact with the friction surface 34 but this contact is not sufficient to interfere with the relative rotation of the clutch members, or to produce objectionable heat, when those members rotate in opposite directions. As here shown, each supporting member is acted upon by a spring 47 to move the same in a direction to maintain contact between the clutch device and the friction surface. Each spring is connected at one end with a projection 48 on the corresponding supporting member 41 and at its other end with a pin 49 mounted in the adjacent plate 43 and the circumferential projection 50 and extending across a narrow portion of said supporting member.

In the normal operation of the hoisting mechanism the motor drives the shaft 25 in a direction to rotate the hoisting drum 16 in load hoisting direction, that is, a direction which will cause the cable to elevate the point of the boom and which is opposite to the direction of rotation of the shaft 25 and the clutch member 29. The hoisting drum when thus rotated by the driving mechanism rotates the clutch member 30 in the direction of rotation of the drum which, as above stated, is opposite the direction of rotation of the member 29. This opposite rotation of the two clutch members causes the clutching devices or friction shoes to be moved to non-clutching positions so that the two clutch members can rotate freely so long as the hoisting drum rotates in load hoisting direction. When the hoisting drum is disconnected from its driving mechanism, either intentionally or accidentally, and is not restrained by the brake, the weight of the load on the drum tends to rotate the same in a reverse or load lowering direction and the force thus exerted on the drum tends to cause the clutch member 30 to rotate in the same direction as the clutch member 29 rotates. The friction surface 34 being at all times in light contact with the clutching shoes any tendency of the clutch member 30 to rotate at a speed greater than the speed of the clutch member 29 will cause the shoes to tightly grip the clutch member 30, thereby locking the member 30 against rotation with relation to the member 29 in the direction in which the latter is rotating and preventing the rotation of the drum in load lowering direction at a speed greater than that permitted by the rotation of the shaft 17 and the clutch member 29. The continued operation of the driving mechanism, in the initial direction, thus causes the load to be lowered at a safe speed. Due to the fact that both clutch members are rotating in the same direction at the time the locking action takes place locking is effected and the lowering of the load is checked without subjecting any part of the mechanism to severe shock or strain. If the drum and clutch member 30 tend to rotate in load lowering direction while the driving mechanism is inoperative the clutching shoes will instantly grip the clutch member 30 and lock the same against such rotation before any appreciable rotation has been imparted thereto, thus positively locking the hoisting drum against rota-

tion in load lowering direction and preventing the downward movement of the boom or other load.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. In a hoisting mechanism comprising a hoisting drum, a load supporting cable wound on said drum, a shaft, means for rotating said shaft, and a driving connection between said shaft and said drum to impart load hoisting rotation to the latter in a direction opposite the direction of rotation of said shaft, a clutch including a member rigidly connected with said shaft, a second member rotatably supported on said shaft and having a friction surface extending about said rigidly connected member, supporting members mounted on said rigidly connected member for rotation therewith and for movement with relation thereto about axes spaced laterally from the axis of said shaft, and friction elements carried by said supporting members and movable to non-clutching positions by the rotation of said second member in a direction opposite the direction of rotation of said rigidly connected member and movable into clutching engagement with said friction surface of said second member by said second member when the latter tends to rotate with relation to said rigidly connected member in the direction of rotation of the latter, and a driving connection between said drum and said second clutch member to rotate the latter in the same direction that said drum rotates.

2. In a hoisting mechanism comprising a hoisting drum, a load supporting cable wound on said drum, a shaft, means for rotating said shaft, and a driving connection between said shaft and said drum to impart load hoisting rotation to the latter in a direction opposite the direction of rotation of said shaft, a clutch including a member rigidly connected with said shaft, a second member rotatably supported on said shaft and having a friction surface extending about said rigidly connected member, supporting members mounted on said rigidly connected member for rotation therewith and for movement with relation thereto about axes spaced laterally from the axis of said shaft, and friction elements carried by said supporting members and movable to non-clutching positions by the rotation of said second member in a direction opposite the direction of rotation of said rigidly connected member and movable into clutching engagement with said friction surface of said second member by said second member when the latter tends to rotate with relation to said rigidly connected member in the direction of rotation of the latter, a driving connection between said drum and said second clutch member to rotate the latter in the same direction that said drum rotates, and yieldable means to hold said friction elements in light contact with said friction surface when said clutch members rotate in opposite directions.

3. In a hoisting mechanism comprising a hoisting drum, a load supporting cable wound on said drum, a shaft, means for rotating said shaft, and a driving connection between said shaft and said drum to impart load hoisting rotation to the latter in a direction opposite the direction of rotation of the shaft, a clutch including a member

rigidly connected with said shaft, a second member rotatably supported on said shaft and having a friction surface extending about said rigidly connected member, said rigidly connected member having circumferentially spaced eccentric bearing surfaces, supporting members mounted for oscillatory movement on the respective bearing surfaces, and friction shoes pivotally mounted on said supporting members and movable into non-clutching relation to said friction surface by

the rotation of said clutch members in opposite directions and into clutching engagement with said friction surface by said second clutch member when rotative force is exerted on said second member in the direction of rotation of the first mentioned clutch member, and a driving connection between said drum and said second clutch member to rotate the latter in the same direction that said drum rotates.
